(57) **CLAIM**

The ornamental design for a swab, as shown and described.

DESCRIPTION

The patent file contains at least one drawing executed in color. Copies of this patent with color drawings will be provided by the Office upon request and payment of the necessary fee.

FIG. 1 is a front perspective view of a swab showing my new design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the portion 8 encircled in FIG. 1;

FIG. 9 is a front perspective view of a swab showing my new design according to a second embodiment;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is an enlarged view of the portion 16 encircled in FIG. 9.

The dashed broken lines in the drawings illustrate portions of the swab that form no part of the claimed design. The dot-dash broken lines in the drawings encircling portions of the claimed design that are illustrated in enlargements form no part of the claimed design.
